UNITED STATES PATENT OFFICE.

SAMUEL M. MANSFIELD, OF THE UNITED STATES ARMY, AND FRANK S. MASON, OF MALDEN, MASSACHUSETTS.

DISAPPEARING-GUN CARRIAGE.

SPECIFICATION forming part of Letters Patent No. 658,028, dated July 3, 1900.

Application filed June 26, 1897. Serial No. 642,468. (No model.)

To all whom it may concern:

Be it known that we, SAMUEL M. MANSFIELD, of the United States Army, and FRANK S. MASON, of Malden, in the county of Middlesex and State of Massachusetts, have invented 5 certain new and useful Improvements in Disappearing-Gun Carriages, of which the following is a specification.

This invention has for its object to provide 10 a disappearing-gun carriage of simple construction which shall be strong and durable and insure the movement of the gun from its firing to its loading position, and vice versa, with an easy movement and without developing 15 a rotative tendency in the gun on its arrival at either position.

The invention consists in the improvements which we will now proceed to describe and claim.

20 Of the accompanying drawings, forming a part of this specification, Figure 1 represents a side elevation of our improved carriage, showing a gun mounted thereon, the parapet behind which the carriage is located being 25 shown in section. Fig. 1^a represents a side elevation of one of the supplemental chassis-plates hereinafter referred to. Fig. 2 represents a section on line 2 2 of Fig. 1. Fig. 3 represents a section on line 3 3 of Fig. 1. Fig. 30 4 represents a top plan view. Fig. 5 represents a front end elevation, the parapet being removed. Figs. 6, 7, and 8 represent views similar to Fig. 1, showing different adjustments of the gun.

35 The same letters of reference indicate the same parts in all the figures.

In the drawings, *a* represents a horizontal turn-table mounted to rotate on a fixed base *b*, having a circular track *c*, between which 40 and the turn-table are interposed suitable antifriction-rolls *d*.

45 *e e* represent two parallel webs or plates affixed to the turn-table and extending rearwardly therefrom and constituting the main chassis of the carriage, said plates being bolted or otherwise secured to the turn-table. The upper edges of the chassis plates or webs are formed as track-rails, supporting wheels on the gun truck or cradle *p*. The rear end of 50 the chassis may be provided with wheels *f f*, arranged to run on a fixed segmental track *g*,

which is concentric with the axis of the turn-table, or, if desired, the turn-table may be of sufficient diameter to support the chassis, in which case the track *g* will not be required. 55

h h represent two parallel plates or webs constituting what may be termed a "supplemental" chassis. Said plates are hinged at their outer end to the main chassis *e e* by any suitable means, such as two segmental plates 60 or hinge members *i i*, one affixed to the main chassis and the other to the supplemental chassis. The plate or member *i* is adapted to slide on the plate or member *i* to permit a vertical swinging movement of the supplemental chassis. The upper edges of the side plates of the supplemental chassis are formed as track-rails adapted to support wheels on the gun truck or cradle *p*.

Mechanism is provided for adjusting the 70 supplemental chassis, the mechanism here shown comprising rack-segments *j*, formed on the plates of the supplemental chassis, a pinion *k*, meshing with said segments and affixed to a shaft *k'*, which is journaled in the main 75 chassis, and an operating-shaft *m*, also journaled in the main chassis and having a hand-wheel *m'* and a pinion *n*, the latter meshing with a gear *o*, affixed to the shaft *k'*. We may, however, employ any other suitable means for 80 adjusting the supplemental chassis.

p represents the truck or cradle, which supports the gun. Said cradle, which may be of any suitable construction, has two pairs of wheels *q q* and *q' q'*. The forward wheels *q q* 85 are arranged to run on the rails of the main chassis, which may be termed a "broad-gage" track, while the rear wheels *q' q'* are nearer together than the forward wheels and are arranged to run on the rails of the supplemental chassis, which may be termed a "narrow-gage" track.

The gun is fixed rigidly to the truck, so that there is no independent swinging movement of the gun therein, the angle of fire of the 95 gun being determined by the relative positions of the adjustable and non-adjustable tracks, as shown in Figs. 6, 7, and 8. Thus naval guns, which are generally made without trunnions, may be used with our improved carriage.

The profiles of the two tracks are formed

to give the center of gravity of the gun a path of movement substantially such as is indicated by the dotted line $z z$, Fig. 1, said path being such that the center of gravity of the gun moves during recoil first along a curve which approximates the parabolic curve which would result from the recoil and the force of gravitation acting conjointly, then along a reverse curve which changes the direction of movement of the said center of gravity, so that the movement is approximately horizontal, (although preferably at a slight downward inclination at the end of the recoil.) The said path may include a straight downward incline between the two curves, as shown, or one curve may run tangentially into the other without an intermediate incline. The result is an easy movement of the center of gravity of the gun from one position of rest to another, the latter part of each movement—namely, to its loading position and to its firing position—being along a practically-straight line, both the muzzle and the breech moving in a straight path at the end of the recoil, so that when the motion is checked there is no tendency of the gun to swing in a vertical plane, the gun moving as a mass in one direction. In all of the disappearing-gun carriages now in use, comprising swinging levers, links, &c., the gun acquires a tendency to rotate or swing in a vertical plane in approaching its firing as well as its loading position. With heavy guns the stresses due to the rotary or swinging motion of the mass are very great and often destructive, being difficult to restrain or check suddenly and a frequent cause of breakage. In our improved carriage, however, this objection does not exist, the gun having no tendency to swing in a vertical plane.

The tracks, as here shown, have curves $x' x'$ of approximately-parabolic form at their forward portions, the curves of the main chassis being preferably formed so that the forward end of the track will have a slight downward inclination to the stops $v v$, which limit the forward movement of the gun, this inclination causing the forward wheels of the truck to bear positively against the said stops. The curves $x x'$ join inclines $x' x^2$, extending downwardly at an angle of about thirty degrees, and from thence the said profiles extend through reversed approximately-parabolic curves $x^2 x^3$ to downward inclines $x^3 x^4$ at an angle of about five degrees, these rear inclines forming the rear portions of the tracks. It is obvious, however, that the curves $x x'$ and $x^2 x^3$ may join each other tangentially without the intervening incline $x' x^2$.

The profiles of the two tracks differ slightly from each other, the difference being such as to cause the muzzle of the gun when the firing-angle is as indicated in either Figs. 1, 6, or 8 to move during recoil along a practically-straight line until it clears the parapet and then through a reversed curve to the loading

position, the path of the muzzle being indicated by the line $y y$ in Fig. 1.

s represents a counterbalance, which is connected with the truck or cradle by wire ropes $t t$ or suitable flexible connections, said ropes passing over pulleys $u u$, which are mounted on a shaft u' , supported in the main chassis. Each rope t may consist of two or more parallel members. The counterbalance s hangs in a well below the turn-table, its weight being sufficient to slightly overcome the weight of the gun, so that the counterbalance normally elevates the gun to its firing position, which is determined by the stops v , here shown as arranged to block the front wheels of the truck.

The pulleys $u u$ are separated sufficiently to permit the barrel of the gun to drop between them when it approaches its loading position. It will be seen that by connecting the counterbalance with the truck by two ropes or cords and guiding said cords by two pulleys separated sufficiently to receive the gun-barrel between them we insure an effective angle of draft of the cords throughout a greater portion of the forward movement of the gun than would be possible if a single cord and pulley were employed, in which case it would be necessary to locate the top of the pulley below the barrel of the gun. The angle of draft may be varied at will by the use of pulleys of different diameters or by adjusting the height of the axis or center of the pulleys.

Any usual or suitable means may be used to check and stop the recoil movement of the gun. We have here shown as the checking means a cylinder w , attached to the rear end of the main chassis, and a piston or plunger w' , projecting therefrom in position to receive the impact of the truck, the cylinder having suitable provisions for retarding the backward movement of the plunger, such as a body of air or liquid permitted to escape slowly from behind the plunger. We do not limit ourselves, however, to the means last described and may use any other suitable means, such as rubber or steel-spring buffers or any of the contrivances heretofore used for this purpose.

w^3 represents a catch, here shown as a hook pivoted to the truck to engage a detent on the chassis, for the purpose of holding the gun in its loading position. In this case the detent is a projection w^3 on the piston of the recoil-check.

It will be seen that the tracks are extended rearwardly beyond the point of engagement of the catch with the detent, so that provision is made for permitting the gun to overrun or move backwardly from its loading position under the influence of heavy charges, the counterbalance returning it to its loading position. Without this provision when relatively-light charges are used the gun would come to rest above the loading position and

be partly exposed to the fire of the enemy, from whence it would have to be laboriously withdrawn by hand-power, thus delaying the service of the gun and preventing safe cover when at rest after discharge.

We do not limit ourselves to the particular mechanical construction and arrangement of parts here shown and may variously modify the same without departing from the spirit of our invention. For example, the plates or webs *h h* constituting the adjustable or supplemental chassis may be outside the plates or webs *e e* of the main chassis, in which case the broad-gage track would be the adjustable one.

15 In case it is not desirable to provide a well under the turn-table, any usual or suitable hydraulic, electric, or other elevating apparatus may be substituted for the counterbalance for elevating the gun to the firing position.

A winch or block and tackle may be provided for pulling the gun down by hand from the firing to the loading position when drilling a gun-crew.

25 We claim—

1. A gun-carriage of the character specified, comprising two tracks of different gage, means for varying the relative positions of said tracks, and a gun truck or cradle engaged 30 with both tracks.

2. A gun-carriage of the character specified, comprising two tracks of different gage, means for vertically adjusting one of said tracks, and a gun truck or cradle engaged with both 35 tracks.

3. A gun-carriage of the character specified, comprising a main chassis constituting a track, an adjustable supplemental chassis constituting another track, means for adjusting the supplemental chassis, and a gun truck or cradle engaged with both tracks.

4. A gun-carriage of the character specified, comprising a main chassis constituting a track, a supplemental chassis constituting 45 another track, a hinge or pivotal connection between the main and the supplemental chassis, means for swinging the supplemental chassis in a vertical plane, and a gun truck or cradle engaged with both tracks.

50 5. A gun-carriage of the character specified, comprising a main chassis having the profiles of its side pieces formed to present alternating salient and reentrant curves, constituting a track, a supplemental chassis having the

profiles of its side pieces formed to present 55 alternating salient and reentrant curves and constituting another track, and a gun truck or cradle engaged with both tracks.

6. A gun-carriage of the character specified, comprising tracks having salient and reentrant curves, and a gun truck or carriage engaged with said tracks.

7. A gun-carriage of the character specified, comprising tracks having elevated salient 65 curves, depressed reentrant curves, and rear inclines extending from the reentrant curves, and a gun truck or cradle engaged with said tracks.

8. A gun-carriage of the character specified, comprising tracks having elevated salient 70 curves, depressed reentrant curves, and rear inclines extending from the reentrant curves, a gun truck or cradle engaged with said tracks, and a recoil-check arranged to permit the gun to overrun its loading position during 75 recoil.

9. In a disappearing-gun carriage, the combination of a gun truck or cradle, a gun immovably affixed to said truck, track rails or members engaged with said truck, two pulleys arranged to permit the depression of the gun-barrel to a point between the pulleys, and a counterbalance connected with the truck by cords passing over said pulleys.

10. In a disappearing-gun carriage, the combination of a gun truck or cradle having two sets of wheels, a gun immovably affixed to said truck, and two tracks of different gage engaged with said wheels, one or both of said tracks being adjustable to determine the angle of fire of the gun.

11. The combination of a gun, a truck or cradle in which the gun is fixed, said truck having two pairs of wheels adapted to tracks of different gage, a broad-gage track engaged 95 with one pair of wheels, a narrow-gage track engaged with the other pair of wheels, and means for adjusting one of said tracks to vary the inclination of the truck and gun.

In testimony whereof we have signed our names to this specification, in the presence of two subscribing witnesses, this 22d day of June, A. D. 1897.
